UNITED STATES PATENT OFFICE

104,142

DESIGN FOR A SCARF

Fjeril Hess, New York, N. Y., assignor to Girl Scouts, (Incorporated), New York, N. Y., a corporation of District of Columbia

Application January 15, 1937, Serial No. 67,074

Term of patent 14 years

To all whom it may concern:

Be it known that I, Fjeril Hess, a citizen of the United States of America, residing in the Borough of Manhattan, city, county, and State of New York, have invented a new, original, and ornamental Design for a Scarf, of which the following is a specification, reference being had to the accompanying drawing, forming a part thereof.

The figure is a plan view of a scarf showing my new design.

I claim:

The ornamental design for a scarf, as shown.
FJERIL HESS.
